George J. Seiss Inventor

By His Attorneys,

Dodson & Roe

UNITED STATES PATENT OFFICE.

GEORGE J. SEISS, OF TOLEDO, OHIO.

DIAPHRAGM HORN.

Application filed May 7, 1921. Serial No. 467,721.

To all whom it may concern:

Be it known that I, GEORGE J. SEISS, a citizen of the United States, residing at Toledo, in the county of Lucas and State of Ohio, have invented a certain new and useful Improvement in Diaphragm Horns, of which the following is a specification.

My invention relates to that class of alarm signals which employ a vibrating diaphragm actuated by the rotation of a toothed wheel, the teeth of which engage a wearing piece secured to the center of the diaphragm.

My invention has for its object to provide a construction for a device of this character which will permit the assembling of the entire operating mechanism before it is placed in the body of the horn, and has for its further object to provide mounting means for the horn which are engaged by the securing means which hold the operative parts together.

My invention has for its further object to overcome unnecessary rattling of the parts when in use, and has for its further object to provide a construction for the horn body which will prevent water from entering the interior thereof.

Other objects will appear from the hereinafter contained description.

My means of accomplishing the foregoing objects may be more readily understood by having reference to the accompanying drawings, which are hereunto annexed and are a part of this specification, in which:

Fig. 1 is a vertical sectional view of a horn constructed in accordance with my invention.

Fig. 2 is a section taken on the line 2—2 in Fig. 1.

Fig. 3 is a rear view of the horn showing the horn support.

Fig. 4 is a fragmentary detail view of the mechanism supporting frame, showing the manner of holding the pivots for the segment.

Fig. 5 is a detail view showing a modified form of construction.

Similar reference numerals refer to similar parts throughout the entire description.

As shown in the drawings, the horn comprises a cylindrical body 10, which is formed in two portions, one of which contains the diaphragm 11, which has the wear-piece 12, secured in the center by means of a nut 13, in the usual manner. The other portion contains the mechanism for vibrating the diaphragm.

In my invention, the operating mechanism is mounted in a U-shaped frame 4, which is clearly seen in Fig. 2 and as shown has two arms 15 and 16, in the ends of which is fixedly mounted a shaft 17, which has a toothed wheel 18, rotatably mounted thereon. A pinion 19, is secured to the wheel 18, although the ball-clutch mechanism 20, which is fully described in my co-pending application, Serial No. 221,601, or any other suitable release mechanism, may be employed if desired. In the rear 21 of the frame 4, is mounted a pin or pivot 22, upon which swings a gear segment 23, the teeth 24 of which are in mesh with the teeth of the pinion 19. The segment 23 is oscillated upon its pivot 22 by an actuating rod 25, which is secured thereto by a pin 26, mounted in the gear segment 23, adjacent its pivot 22. The upper end 27, of the actuating rod 25 extends through an opening 28, formed in the wall of the body portion and is provided with a button 29, for convenient manual operation. In order to prevent the entrance of water through the opening 28, I form it with an annular lip or flange 30 which has the added effect of increasing the bearing surface for the reciprocation of the rod 25.

The inner end 31, of the actuating rod 25, is provided with an extension which terminates in a hook 32 which is adapted to engage one end of a coil spring 34, the other end of which is secured to a lug, which projects from the wall of the body portion. The coil spring 34, serves two purposes, first its function is to hold the actuating rod 25 normally in a projected position and to return it automatically when it has been depressed; the other, is to prevent the rod from rattling against the edge of the opening 28. It is necessary for the rod 25 to

have a free movement and as a consequence, an annoying rattle is produced by the rod striking against the edge of the opening 28; but in the construction I have described, 5 the spring 34, exerts just enough pressure to prevent the rattle, without interfering with the free movement of the rod.

Screw threaded openings 35 and 36 are provided in the arms 15 and 16, adjacent 10 the ends of the shaft 17, and adapted to register with openings 38 and 39, formed in the rear body portion which latter are adapted to register with the openings 40 and 41, formed in the wall of the forward body portion. 15

The horn is carried by a supporting frame 42, which is provided with two arms 43 and 44, which are bent to coincide with the curve of the body portion and are provided with 20 openings 45 and 46, to receive the securing screws 47 and 48.

The frame 42 has a central member 49, which engages the lower part of the wall of the body portion thus preventing its 25 rocking.

In assembling the horn, the pinion 19 is secured to the wheel 18, and the two are then slipped on the shaft 17. A shoulder is necessary to prevent the lateral movement 30 of the wheel 18, and I have found an inexpensive means of forming one by placing a piece of tubing 50, over the shaft 17, of the proper length to hold the wheel 18 in the proper position. The shaft is then 35 fastened in the ends of the arms 15 and 16, of the frame 4. The gear segment 23, is then placed in position and the pivot pin 22, inserted in its place, which is formed by a recess cast or punched in the rear wall 40 of the frame 4. The actuating rod 25 is then secured to the gear segment 23, by means of the pin 26. The mechanism is now ready for mounting in the body portion. This is done by passing the end of 45 the rod 25, through the opening and sliding the frame 4, back until its rear abuts against the end 52, of the cylindrical body portion when a securing screw 53, is secured into the frame, thus serving to hold the 50 frame 4 in position and also to prevent, by the projection of its inner end, any dislodgment of the pin 22.

The coil spring 34, is then hooked to the lug and its lower end caused to engage the 55 hook 33, on the end of the rod 25. The forward body portion is then telescoped into the rear body portion until the openings 35, 36, 45 and 46, are all in register when the supporting frame 42, is placed in position 60 and the securing screws 47 and 48 are screwed in position, holding all parts rigidly and securely together. The button 29, is then secured to the rod 25, and the horn is ready for use. It will be seen from the foregoing 65 that the difficult work of assembling

the operative mechanism can all be done prior to its installation in the body of the horn.

Having described my invention what I regard as new and desire to secure by Let- 70 ters Patent is:

1. The combination with a cylindrical body formed in two parts, of a U-shaped mechanism supporting frame, secured to the rear and side walls, the rear wall of the frame having a recess stamped therein, a pivot in said recess, a gear segment mounted on said pivot, the securing means in the end wall operating to prevent the longitudinal movement of the pivot, a shaft fixedly secured to the ends of said frame, a toothed wheel rotatably mounted on said shaft, a pinion secured to said wheel, the teeth of said pinion meshing with the teeth on said segment, means to move said segment from 80 outside of said body, and means to automatically return said segment to its normal position.

2. The combination with a cylindrical body of a U-shaped mechanism supporting 90 frame secured to the rear and side walls of said body, a pivot mounted in the rear wall of the frame, means to prevent the longitudinal movement of said pivot, a gear segment mounted on said pivot, a shaft fixedly 95 secured in the ends of said frame, a toothed wheel rotatably mounted on said shaft, a pinion rotatably mounted on said shaft, said pinion being secured to the toothed wheel, the teeth of the pinion meshing with the 100 teeth on the segment, a vertical rod to move said segment from outside of said body and means to normally hold said rod projected outwardly.

3. The combination with a cylindrical 105 body formed in two parts, of a mechanism supporting frame, means to secure said frame to the side and end walls of said body, a gear segment pivoted to said frame, a shaft fixedly secured to the ends of said frame, a 110 toothed wheel rotatably mounted on said shaft, a pinion rotatable on said shaft, said pinion being secured to said wheel, the teeth of said pinion meshing with the teeth on said segment, means to move said segment 115 from outside of said body, and means to automatically return said segment to its normal position.

4. The combination with a cylindrical body formed in two parts, of a U-shaped 120 mechanism supporting frame, a gear segment, there being a recess in the rear of said frame, a pivot mounted in said recess upon which the segment oscillates, a shaft fixedly secured to the ends of said frame, a 125 toothed wheel rotatably mounted on said shaft, a pinion rotatably mounted on said shaft, means to cause the movement of said pinion in one direction to rotate the toothed wheel but not in the other, the teeth of said 130

pinion meshing with the teeth on said segment, a vertical rod which oscillates said segment from outside of said body, and means to automatically return said rod to its normal 5 position.

5. The combination with a cylindrical body formed in two parts, of a mechanism supporting frame, a gear segment, a shaft fixedly secured to the ends of the said frame, 10 a toothed wheel rotatably mounted on said shaft, a pinion secured to said wheel, the teeth of said pinion meshing with the teeth on said segment, means to move said segment from outside of said body, and means 15 to automatically return said segment to its normal position, means to secure said frame in the interior of one of the body portions, said means passing through both body portions, a diaphragm secured at one end of 20 one of the cylindrical body portions, a wear piece thereon which is engaged by the teeth of the wheel.

6. The combination with a cylindrical body formed in two parts, of a supporting frame having two upwardly extending arms, the arms of which are fitted to and coincide with the periphery of the cylindrical body, means to clamp the supporting frame, body portion and mechanism supporting frame, 25 30 rigidly together.

7. The combination with a cylindrical body, of a mechanism supporting frame, a gear segment pivoted to said frame, a shaft fixedly secured to the ends of said frame, a toothed wheel rotatably mounted on said shaft, a tube mounted on said shaft, the end of which abuts against the wheel, a pinion secured to said wheel, the teeth of said pinion meshing with the teeth on said segment, 35 means to move said segment from outside of said body, and means to automatically return said segment to its normal position.

8. The combination with a cup-shaped body portion, a diaphragm closing the open 40 end thereof, a wear-piece in the center of the diaphragm, a gear segment, the teeth of which engage said wear-piece, a pivot secured to the rear wall of the cup-shaped portion on which said segment swings, an actuating rod pivotally secured to said segment adjacent the pivot pin, said rod extending to the exterior of the cup-shaped portion, a button on the end of said rod, a coil-spring intermediate the end of the rod and the wall 45 50 55 of the body portion.

9. The combination with a cylindrical body formed in two parts, of a mechanism supporting frame, means to secure said frame to the side and end walls of said 60 body, a gear segment pivoted to said frame, a shaft fixedly secured to the ends of said frame, a toothed wheel rotatably mounted on said shaft, a pinion secured to said wheel, the teeth of said pinion meshing with the teeth on said segment, a vertical rod pivot- 65

ally attached to said segment, which rod extends through the top of the body portion, an extension on the inner end of said rod, a coil spring, one end of which is secured to the top of the cylindrical body, the other end 70 engaging the said extension, said spring operating to automatically return said segment to its normal position.

10. The combination with a cylindrical body formed in two parts, of a mechanism 75 supporting frame, a gear segment pivoted to said frame, a shaft fixedly secured to the ends of said frame, a toothed wheel rotatably mounted on said shaft, a pinion secured to said wheel, the teeth of said pinion meshing with the teeth on said segment, and means to automatically return said segment to its normal position, there being an opening in the top of said body, a vertical actuating rod which extends through said 80 opening to the outside of the cylindrical body and means to pivotally connect said rod to said segment adjacent its pivot pin.

11. The combination with a cylindrical body formed in two parts, of a mechanism 90 supporting frame, means to secure said frame to the side and end walls of said body, a gear segment pivoted to said frame, a shaft fixedly secured to the ends of said frame, a toothed wheel rotatably mounted on said 95 shaft, a pinion secured to said wheel, the teeth of said pinion meshing with the teeth on said segment, a vertical rod pivoted to said segment, an extension on the inner end of said rod, a coil spring, one end of which is secured to the top of the cylindrical body, the other end engaging the said extension, said spring operating to hold said rod normally in a projected position and to cause a pressure of the side of the rod against the edge 100 of the opening, and means to automatically 105 return said segment and rod to its normal position.

12. The combination with a cylindrical body formed in two parts, of a U-shaped mechanism supporting frame, a gear segment pivoted to said frame, a shaft fixedly secured to the ends of said frame, a toothed wheel rotatably mounted on said shaft, a pinion secured to said wheel, the teeth of said pinion meshing with the teeth on said segment, there being an opening in the said body, a lip around said opening, a vertical actuating rod which extends through said opening to the outside of the cylindrical body and pivotally connected to said segment adjacent its pivot pin.

13. The combination with a cylindrical body formed in two parts which telescope 110 each other adjacent the longitudinal center, of a U-shaped mechanism supporting frame, means to secure said frame to the side and end walls of said body, a gear segment, a pivot mounted in a recess formed 115 in the rear of said frame on which said 120 125 130

segment is mounted, a shaft fixedly secured to the ends of said frame; a toothed wheel rotatably mounted on said shaft, a pinion secured to said wheel, the teeth of said pinion meshing with the teeth on said segment, a pivoted vertical rod to move said segment from outside of said body, an extension on the inner end of said rod, a coil spring, one end of which is secured to the

top of the cylindrical body, the other engaging the said extension, said spring operating to hold said rod normally in a projected position, and to cause a pressure of the side of the rod against the edge of the opening, a button on the end of said rod.

In testimony whereof, I have signed the foregoing specification.

GEORGE J. SEISS.
